LEO A. MELTZER, OF SEATTLE, WASHINGTON

CAN LINER

Application filed January 6, 1932. Serial No. 585,138.

My invention relates to an improvement in liners for cans. It is particularly intended for use in connection with cans to receive garbage and like material. Such matter is likely to be moist, and therefore to stick to and become foul in the can if allowed to come in direct contact therewith. It is an object of my invention, in addition to the general object of preventing fouling of the can and enabling easy removal of the garbage therefrom, to provide an inexpensive liner which can be shipped and handled in flat condition, circular, square, or otherwise shaped to fit the can, which can be easily applied to and supported from the upper edge of the can, which is of material that is inherently resistant to unfolding—for instance, heavy paraffined paper—so that it does not drop immediately to the bottom of the can, but only drops gradually as additional waste is placed thereon, which may have stiffening members associated with its bottom to maintain the bottom distended, and which may have as a part of the liner an interfolded top of the same material which, because of its resistance to unfolding, will unfold substantially alike and completely, and which, when released, will fly back to the folded position so that it is easy in the first place to insert matter into the can, and in the second place, it is certain that the garbage placed inside will not be left uncovered.

My invention comprises the novel liner as an article of manufacture, and the novel associated elements, as shown in the accompanying drawing, described in the specification, and as will be more particularly defined by the claims which terminate the same.

In the accompanying drawing I have shown my invention embodied in a form which at present is preferred by me, it being understood that certain elements thereof may be omitted, if it is not desired to employ the same.

Figure 1 is a perspective view of my liner in the form in which it would be shipped and distributed.

Figure 2 is a vertical axial sectional view

through a garbage can, with my liner applied thereto, and a small amount of garbage within the can, the can cover being shown in place.

Figure 3 is a view similar to Figure 2, illustrating the can nearly full, the liner fully extended, and the liner cover unfolded to permit the insertion of more material.

Figure 4 is a plan view of the can and liner as seen in Figure 3.

Figure 5 is a perspective view of the stiffening means which may be associated with the bottom of the liner.

The liner is preferably formed of paper, and as I have indicated, I prefer to employ a heavy, stiff paper which is paraffined to resist moisture, and which will have the inherent quality of resisting unfolding. Such a liner 1 is made in tubular form and is folded after the fashion of an accordion, as is best illustrated in Figure 1, the ridges 10 extending circumferentially. The excess of material may be taken up in any suitable way, for instance, by very small longitudinal plaits in the several valleys.

The bottom 11 is secured entirely about its periphery to the lower end of the tube 1, which prevents leakage of moisture, and there may be associated with the bottom a stiffening means, such as the hoop 2 and the cross wires 20. This may be secured to or beneath the bottom in any suitable fashion.

At the upper end of the tube means are provided for supporting it from the upper part of the garbage can 3 in which it is to be placed, and such means may conveniently comprise the hooks 4 which hook over the upper edge of the can, and which are secured to only the upper part of the liner. The flange 31 of the can cover fits on outside of these hooks 4.

The liner may be left thus and will serve a very useful purpose, as is evident. When first applied within the can the hooks 4 support the liner, and because of the inherent resistance of the material to unfolding, the bottom 11 will lie well above the bottom 32 of the can. As material is placed in the liner, however, the accordion folds will relax under the weight of the material, and

the bottom 11 will sink down until finally it rests upon the bottom 32 of the can, the liner being preferably made of a length such as to permit this.

5 For a number of reasons, among which is the desirability of protecting the inside of the can top 30 from contact with the material inside, and to insure that the garbage will always be covered in some manner at least, it is preferable to provide a cover 5 of the same material as the liner, and this may be formed as an upward continuation of the same tube. Its height is such that it may be folded in a whorl, as best seen in Figures 10 1 and 4, so that the edges all meet at the center, each fold 50 of the whorl lying over one and under another. Thus, due to the stiffness of the material, upon pulling aside any portion of the cover 5, the remainder, 15 to some extent at least, will open also, and thus there is provided an opening through which garbage may be dropped into the can. Upon release of the top 5, however, the resistance of the material asserts itself and 20 25 to some extent at least, will open also, and thus there is provided an opening through which garbage may be dropped into the can. Upon release of the top 5, however, the resistance of the material asserts itself and the top refolds and substantially closes the entrance to the can. It is, of course, intended that the can cover 30 shall be employed in addition.

Such a cover will prevent direct contact 30 between the can and the contents, and when the can is filled, the liner can be drawn out with the contained garbage, and the entire package dropped as a unit into the collecting truck, and be thus carried away 35 without the necessity of exposure of the contents to the air, and this is particularly made possible because of the employment of the cover member 5 and the employment of the peculiar whorl interfolding thereof. To 40 aid in closing the top, so that the contents can not spill out when the filled liner has been removed from the can, strings 6 may be provided at the top of the liner. These can be tied around the top of the liner to 45 keep its top closed upon removal.

Should it be found desirable to employ a hoop at the entrance to the liner—that is, about its upper end—it will be apparent that the same might be associated with the 50 liner in various ways, and the supporting hooks 4 would be attached thereto.

What I claim as my invention is:

1. A can liner of paraffined paper or the like having an inherent resistance to unfolding, comprising an accordion-folded tube of slightly smaller diameter than the can in connection with which it is to be used so as to be substantially spaced at all times from the walls thereof, a bottom of substantially the diameter of the tube secured thereto entirely about its periphery, means to support the upper end of the tube from the upper part of the can, to leave the tube otherwise unsupported, and stiffening means 55 associated with the bottom to maintain it

distended under the weight of material placed thereon.

2. A can liner of paraffined paper or the like having an inherent resistance to unfolding, comprising an accordion-folded tube of 70 slightly smaller diameter than the can in connection with which it is to be used so as to be substantially spaced at all times from the walls thereof, a bottom of substantially the diameter of the tube secured thereto entirely about its periphery, means to support the upper end of the tube from the upper part of the can, to leave the tube otherwise unsupported, stiffening means 75 associated with the bottom to maintain it distended under the weight of material placed thereon, and a top of the same material comprising an upward continuation of the tube folded in a whorl about the center to close the top of the tube, and by its inherent stiffness tending to remain closed. 80

3. In a garbage receptacle, in combination with a stiff container, a liner comprising a longitudinally distensible tube of substantially constant transverse area, and of 90 slightly smaller diameter than the container received within and substantially spaced at all times from the walls of the container, and means for supporting the liner from the upper edge of the receptacle. 95

4. The combination of claim 3, the tube having a self-closing top closure integral therewith to prevent contact of the container cover with garbage in the tube.

Signed at Seattle, King County, Washington, this 31st day of December, 1931. 100
